UNITED STATES PATENT OFFICE.

CHARLES HENRY FISHER, OF LOWELL, MASSACHUSETTS, ASSIGNOR TO THE
LOWELL MACHINE SHOP, OF SAME PLACE.

SIZING-VAT.

SPECIFICATION forming part of Letters Patent No. 362,735, dated May 10, 1887.

Application filed October 5, 1886. Serial No. 215,381. (No model.)

To all whom it may concern:

Be it known that I, CHARLES HENRY FISHER, a citizen of the United States, residing at Lowell, in the county of Middlesex and State of Massachusetts, have invented a new and useful Improvement in Sizing-Vats, of which the following is a specification.

My invention relates to that class of sizing-vats where yarn or other textile material is operated upon in a continuous manner, the material passing through the vat with considerable speed and being treated with size or other suitable substance during its passage.

The object of my invention is to provide a reliable means of controlling the temperature of the substance—such as size—with which the textile material is treated, and a more inexpensive method of construction than has hitherto been adopted in similar circumstances.

My invention is illustrated in the accompanying drawings, in which—

Figure 1 is an end elevation of the treating-vat. Fig. 2 is a side elevation of the said vat. Fig. 3 is a plan showing the top of the improved heating apparatus; and Fig. 4 is a sectional elevation of the heating apparatus at the line *a a* of Fig. 3, with the vat-sides attached thereto, and showing a usual method of connecting these parts together.

Similar reference-numbers refer to similar parts in all the views.

It is usually desirable, when textile materials are to be treated with hot liquids or semi-liquid substances—such as size—to be able to evenly, quickly, and safely bring the substance which is to be applied to the textile material to some desirable and fixed temperature, and vats much resembling my improved apparatus in outward appearance have been in use for such purposes for a considerable time. With some of these older forms of apparatus I have found, when the material in the vat is to be heated with steam or hot air, that cold air is likely to collect in a body in some portions of the heating-chamber, preventing the said chamber from becoming uniformly heated by the hot fluid, which is caused to pass through the chamber for the purpose of heating it. This uneven heating of the heating-chamber leads to unequal heating of the contents of the vat,

necessitating a considerable amount of care and skill in the use of the vat, in order to properly perform the operations conducted therewith. With my improved vat this difficulty of unequal heating does not exist.

The drawings represent a vat which is especially designed for applying hot size to the surface of yarn, and in those drawings the course taken by the yarn while passing through the vat is represented by the line 1. Several hundred threads are usually sized at once, the threads passing along through the machine side by side and at the same rate of speed. The yarn is shown as passing first over the guide-rolls 2, thence under the immersing-roll 3, and then between the pairs of squeezing-rolls 4 and 5. One of these squeezing-rolls is usually a heavy top roll, 4, which presses the size into the yarn as it passes through the rolls, and sometimes, when it is desirable to do so, a still greater pressure is applied to the yarn by means of levers 6 and weights 7 attached thereto, which press upon the axle of a squeeze-roll. The yarn is caused to move through the vat by means of the squeeze-rolls, the lower roll, 5, of each pair of which is driven by a gear-wheel, 8, upon its axle 9. The gears 8 are driven from machinery or shafting at a distance from the vat by means of the shaft 10, the bevel-gears 11 and 12, and the spur-gear 13. 80

Any other usual and convenient means of manipulating the textile material as it passes through the vat may be substituted for that which is shown.

The vat which retains the size or other substance with which the textile material is to be treated is preferably made, as shown in the drawings, by clamping the flanged sides 14, which also preferably support the mechanism for treating the textile material, upon the top 90 of the heating-chamber 15, the said chamber being in turn supported by legs 16. The heating-chamber is provided with partitions 17, which so divide the space between its upper and lower sides, as shown in Figs. 3 and 4, that 95 steam or other heating agent, or in some cases cold water or other cooling agent, which is introduced through the pipe 18 into the said space, will be caused to move, if at all, in such a manner as to come successively in contact 100

with every portion of the plate that forms the top of the heating-chamber and that is in contact with the substance which is in the vat above. By thus causing the heating agent 5 to positively circulate in the interior of the heating-chamber every portion of the said heating-plate will be uniformly heated, and thus will evenly heat all portions of the substance in the vat above, and any cold air that 10 is in the heating-chamber will be driven ahead of the steam or other heating agent out of the pipe 19.

The pipes 18 and 19 are usually provided with regulating-valves 20, and the heating-chamber with a safety-valve, 21, which safety-valve may be so adjusted that the pressure and the temperature of the steam in the heating-chamber can never rise to such an amount 15 as to injure either the heating-chamber or the 20 contents of the vat above.

Whenever it can be done I prefer to make the heating-chamber 15 in a single casting, as shown in the drawings, for the sake of reducing its cost. In that case I am able to use any 25 necessary pressure in the interior of the heating-chamber, the partitions 17 acting as stays to prevent the sides of the chamber from being forced apart by the pressure, while the bottom of the vat is left smooth, with no heads of 30 stay-bolts exposed to the contents thereof. I am, however, aware that if for any reason it is desirable to make the heating-chamber in more than one piece, such a construction may be adopted. It may sometimes be desirable to 35 make the upper and lower plates of the heating-chamber in separate pieces, in which case they may be secured together by stay-bolts in

the manner which is usually adopted in such constructions, the partitions 17 in that case being cast wholly upon one or the other of the 40 said plates, or partially on each, or entirely separate from either, as may be most convenient. I, however, prefer to cast the heating-chamber in a single piece whenever it can be done. Holes in the edges of the heating-chamber 45 that are finally closed by screw-plugs 22, or other equivalent means, allow the introduction of tools for breaking up the internal core, which it is necessary to use while the heating-chamber is being thus cast in a single piece. 50

What I claim as new, and desire to secure by Letters Patent, is—

The sizing apparatus which consists of the size-containing vessel, means for subjecting a textile material to size that is contained in the said vessel, a heating-chamber in contact with the said size and whose interior space is divided by partitions, whereby a hot fluid passing through the said chamber will be forced by the said partitions to come successively in contact with the different portions of that side of the said heating-chamber which is in contact with the size, means for introducing into and removing from the said heating-chamber a hot fluid, means for controlling the rapidity 60 of the passage of the said fluid through the said chamber, and means for preventing the pressure and temperature of the said hot fluid from rising to an injurious amount, substantially as set forth.

CHARLES HENRY FISHER.
